(57) **CLAIM**

The ornamental design for a protective cap for gable end of roof ridge, as shown and described.

DESCRIPTION

FIG. 1 is a perspective view of a protective cap for gable end of roof ridge showing my new design;

FIG. 2 is a top view thereof;

FIG. 3 is a front side view thereof;

FIG. 4 is a right side view thereof, the left side view being a mirror image thereof; and,

FIG. 5 is a bottom view thereof.

1 Claim, 4 Drawing Sheets

FIG. 1

FIG. 2

FIG. 3

FIG. 4

FIG. 5
